PROTECTION OF BORE SURFACES OF GUNS

Henry B. Allen and Nicol H. Smith, Philadelphia,
Pa., assignors to the United States of America
as represented by the Secretary of War

Application April 28, 1945, Serial No. 590,846

6 Claims. (Cl. 89—14)

1

The invention relates to means for protecting and prolonging the life of the throat and rifling in ordnance pieces, and seeks particularly to present means especially applicable to use in current gun models with little modification. It is well understood that erosion at the forcing cone and adjacent rifling by the highly heated and rapidly moving gases at the high pressures involved in the gun chamber, and the diversion and compression thereof in the throat marks the beginning of deterioration of bore faces and rifling. This is soon followed by a condition whereon firing shock and shearing effects occur by the projectile moving without rotation from the chamber over a part of the bore where rifling has been destroyed, and then encountering partly eroded rifling after considerable acceleration. This may then become the major factor in deterioration of the bore.

An object of our invention is the provision of an effective and thoroughly reliable method for protecting the bore surfaces of guns from influences of a wide variety which otherwise lead to erosion and untimely wearing out of the gun.

A further object of our invention is the provision of mechanically simple and inexpensive means for protecting the bore surface of a gun from wear and deterioration by propellant explosives, which may be included in the ammunition as loaded into the gun incidental to simple firing routine.

A principal aim of the invention is to provide an expendable inexpensive facing or chambering element in the round itself which will afford a surface material sufficient to withstand the erosion manifest in firing the single round at least, this material extending over only the critical area where erosion has heretofore been observed to start in conventional bores, so that the further deterioration by shock and shear after initial erosion will be avoided, as well as erosion otherwise materially reduced.

A still further object of our invention is the provision of a gun which is adapted to receive chambering rounds of ammunition including bore surface protective means.

Other objects of the invention will be obvious, and in part pointed out hereinafter.

The invention accordingly consists in the individual elements, combination of parts, composition of materials, and in the several steps, and the relation of each of the same to one or more of the others as described herein, taken in the light of the accompanying drawings: and set forth in the following claims.

In the drawings herewith Fig. 1 is a longitud-

2

inal sectional view of a round of ammunition embodying certain features of our invention;

Figure 2 is a detail elevation of the sleeve;

Figure 3 is a fragmentary section of a round showing the standard .50 caliber bullet and a short sleeve;

Figure 4 is a fragmentary longitudinal section of a gun barrel, more particularly of chamber and bore portions;

Figure 5 is a longitudinal section of the barrel and round illustrated in Figures 1 and 4, the representations of land forms being purely formal;

Figure 6 is a similar view showing the use of a short liner sleeve with modification of the barrel;

Figure 7 is a similar view showing the invention adapted to the current ball ammunition.

As conducive to a clearer understanding of certain features of our invention it may be noted at this point that gun erosion is a complex phenomenon involving a combination of numerous effects; predominantly thermal effects, chemical and metallurgical effects, and mechanical effects, all of which contribute, as the result of gun use, to shortening the useful life of the gun. The individual or combined intensity of the various effects is dependent upon such factors as gun material, type and quantity of powder and type of projectile employed, rate of fire, and velocity of projectile. Gun erosion is most severe within

30 an area beginning at the forcing cone and origin of rifling and extending some few calibers along the gun barrel toward the muzzle.

As the result of high temperatures reached by the powder gases, a thin layer of metal at and 35 near the bore surface of the gun is rapidly heated to a temperature which, under certain circumstances, exceeds melting range of the metal. Even if the bore surface is not melted, the temperatures reached are such as to reduce the 40 strength of the steel and facilitate its displacement. In cases where gas leakage occurs the material may be simultaneously melted and carried away to a marked degree by scouring action of the escaping gas.

45 At the high temperatures attained by the powder gases the products of powder explosion are chemically active. Furthermore, the raising of the bore surface temperature increases the chemical reactivity of the gun material. As a 50 result, there is a very complex set of reactions between the gun material and the powder gases. The importance of chemistry in the erosion process has not as yet been fully evaluated, but the existence of a considerable variety of reaction products has been established.

In sustained or rapid firing of a gun the temperature attained by the steel bore surface is well above the alpha-gamma transformation point of iron. A transformed surface layer consequently develops to some thousandths of an inch thickness which differs markedly in its metallurgical characteristics from the underlying steel. It will be appreciated that in the rise of temperature of the barrel to the gamma transformation point, the critical temperatures of both the alpha and 10 beta allotropes are exceeded. This layer has lower strength, probably a lower melting point due to chemical effects, and seemingly is less resistant to erosion than the underlying steel.

There are several mechanical effects which are known to contribute to the erosion process. In the first place, simple frictional or abrasive wear by contact of the projectile is a factor, the importance of which depends upon gun and projectile design and materials. When the steel surface of a projectile bears upon a bore surface of steel, galling may occur in addition to abrasive wear, with consequent removal of small masses of metal from the bore surface. Both the abrasive wear and galling tendency are affected by the surface temperatures attained in the bore. The temperature at the point of rubbing is influenced by the instantaneous heating effect caused by friction.

It is also to be noted that in conventional guns bore diameter is increased at the bore surface as a result of intense surface stresses developed by engraving. This is particularly true under rapid fire conditions, when the gun is quite hot. Metal in the lands is displaced radially outward, forward, and circumferentially sideways. Even though no metal is actually removed, the lands are gradually obliterated, by being hammered, swaged or pressed down into the surface from which they at first rose and by being broadened and extended by flattening. Any downward radial displacement of that portion of a land under the projectile rotating band is accompanied by an upward displacement of the land surface ahead of it. In effect a wave, consisting of a depression of the land material near the origin of rifling and a raising of material in front of this point proceeds down the bore as firing progresses.

An outstanding object of our invention, accordingly, is the provision of a method for conditioning guns so as to improve gun resistance to plastic deformation and to erosion normally produced by thermal, chemical, metallurgical, and mechanical effects—combined or separately—incident to firing of conventional ammunition.

Referring now more particularly to the practice of our invention, we increase the useful life of any of a wide variety of smooth bore or rifled guns of different sizes to be employed for automatic or single shot fire at high or low velocity, through the use of thin sleeves which provide a protective covering for the bore surface of the gun over at least that part where most severe erosion and deformation commonly occur. The sleeves preferably are affixed as individual elements to the cases of fixed ammunition to be fired in the gun, or—illustratively—may constitute integral extended portions of such cases, so as in either event to be insertable or ejectable with the case in the normal firing function of the gun.

In order to make sleeve protection of the bore surfaces practicable at the breech end of the bore we prefer to provide a gun which has a slightly enlarged bore including the forcing cone and extending for a distance toward the muzzle sufficient to permit and ensure proper chamber-

ing of the ammunition including the sleeve. Aside from the feature just mentioned, the gun barrels conveniently are wholly of conventional contour along the bore surface. Preferably, but not essentially, the bore surface, illustratively at least that part immediately in advance of the enlarged bore portion and continuing forward to the muzzle, is of chromium or other erosion-resistant material.

In Figure 1 of the accompanying drawing there is represented at 10 an illustrative round of case ammunition which we employ in the practice of our invention. The particular round shown corresponds to one of artillery type used by us in a .50 caliber rifled gun, although the invention may be also used on the conventional .50 caliber ammunition with boat-tailed soft jacketed bullet now generally in use in .50 caliber automatic guns. The current form of such gun, standard in the United States Army is shown in patents to Browning, Nos. 1,293,022, and 1,628,226. It includes a standard brass cartridge case 11 containing a suitable powder charge and having the usual primer centered in the base thereof. The forward part of the case comprises a tapered shoulder portion 12 which terminates in a conventional open neck 13. An artillery type projectile or bullet 14 (of approximately 0.5 inch diameter) fits firmly into the open neck and has an interposed rotating band 15 set within and extending forwardly of the outer edge of the neck.

A thin sleeve 16, illustratively made of drawn soft steel tubing and having a wall thickness of about 0.010 inch, is mounted over the case neck. 35 It is formed with a large diameter rear part 17, and tapers down before—but not necessarily engaging—the projectile rotating band as at 18, so as to provide forwardly a slightly reduced cylindrical forward part 19 having an inner diameter which is slightly more than 0.500 inch. On this diameter the sleeve extends from near the rotating band forwardly over the surface of the projectile to a distance somewhat in advance of the projectile nose in this particular form. The 45 sleeve, for the sake of simplicity of assembling, preferably is made so as to be slipped readily into this position on the round after manufacture of the standard prior round. In order to ensure proper withdrawal of the sleeve when the cartridge is extracted by breech mechanism after the round has been fired, we provide several peripherally spaced indentations or perforations 20 in the sleeve near the base of the same preferably located so as to be rearwardly of the bullet 50 as in Fig. 1. The holes may be circular, or rectangular as in Fig. 2, to afford better keying with the cartridge. When the round is fired, metal of the case neck is forced permanently into the perforations by powder gas pressure within the case, to effect a positive lock between the case and the 55 sleeve.

For firing the ammunition, we provide a gun having a rifled barrel 21 (see Fig. 4 of the drawing) which is modified adjacent the chamber to 65 accommodate the sleeve element 16. The forward part or neck 27 of the chamber, the forcing cone 24 and adjacent relieved section 22 of the rifled bore, are enlarged in radius as compared with conventional guns by an amount which is substantially equal to the thickness of the sleeve. It will be noted that the rifling 23 extends from the forcing cone 24 forward along the bore surface of the enlarged bore section 22, then is stepped or inclined inward at 25 and continued conventionally through the advanced portion 26 of the bore,

which may be of conventional caliber and length. With a round of sleeved ammunition properly chambered in the modified gun, as illustrated in Fig. 5 of the drawing, the bullet rotating band 15 is disposed immediately in back of the forcing cone 24. The forcing cone and rifled bore surface extending therefrom are separated from the bullet by sleeve 16 which rests on or is substantially geometrically congruous with the bore surface, including the forcing cone and land tops 28 of the enlarged bore section. At its advanced end the sleeve adjoins the .50 caliber section of the rifled bore and is substantially aligned, inside, with the land tops of the same.

When the gun is fired, using the round of Fig. 1, the bullet 14 carries rotating band 15 past forcing cone 24, at which time engraving of the band by means of the rifling begins through sleeve 16. The sleeve also is actually engraved by extrusion into the grooves along with the rotating band. Before and during this period metal of the shell case 11 is forced by powder gas pressure into the perforations 20 at the base of the sleeve for locking or keying the two elements together. The sleeve protects the underlying metal of the gun from erosive effects of the hot powder gases as well as from mechanical effects set up at the forcing cone and by subsequent engraving: also by insulation of heat from the tube material. After the bullet reaches the end of the sleeve, additional engraving of the band or bullet case which may be necessary takes place in the advanced bore section. After firing, the hot case and hot sleeve attached or keyed thereto are ejected from the gun by the usual breech mechanism operating on the case (removing a substantial amount of heat which was prevented from reaching the barrel), followed by loading, firing and ejection of successive similar sleeved rounds as desired. The overall effect is to relieve the gun bore surface of exposure to the most severe conditions which normally contribute to erosion and plastic deformation, with the result that useful life of the gun is considerably increased.

While it is desirable to extend the protection of the forcing cone 24 and rifling in the bore as far toward the muzzle as practicable there is a limit to the practicability of extension of the sleeve and also a point of economic balance and compensation between the benefit of prolongation of life of the weapon by this method and cost of modified ammunition and gun, modification of handling routine, and modification of belts and firing mechanism. The sleeve of Fig. 1 has been found practicable, but in order to limit expenditure of material and for other reasons it has also been found very beneficial to use a sleeve which does not extend beyond the bourrelet or possibly the beginning of the ogive. This is especially satisfactory when the bore forwardly of the sleeve 16 (or 16' hereinafter described) is faced with a wear resisting material. There is a peculiar coordination of these two features practicable which is distinguished from merely facing the gun surfaces with wear resistant material. Thus, the hard materials available and suitable for the use are scarce and expensive; they can only be practicably applied in thin facings; facings which are effective to assure an adequate length of service to bore faces at a distance from the conventional chamber are incapable of preventing deformation of underlying material of the gun tube at the forcing cone, due to high temperatures effective through an otherwise adequate facing, and would permit plasticising and deformation of such un-

derlying material. But with the use of the short sleeve (Fig. 3) and its repeated renewal on each round, the lowering of temperature of the gun tube material by absorption and impedance in the sleeve and by conduction to the fresh sleeves; a moderate degree of insulation, and the dissipation of heat by the removed sleeves; as well as protection of the overlying material of the gun tube against erosion, enable a very extended use of the gun with immaterial depreciation of the forcing cone and adjacent rifling, and practically no wear of the forward rifling, when the thin facing is used from the chamber forward.

In Figure 3, the sleeve and parts corresponding to those already described in the sleeve 16, have the same reference characters with the addition of a prime mark. The cartridge case is unchanged, and the rear larger part 17' of the sleeve is of the same thickness, diameter and length as the part 17; the taper 18' is the same as the part 18 of sleeve 16, but the forward reduced part 19' of this sleeve, while of the same thickness and diameter as in the forward part of the sleeve 16, is only about one half—or less than half—the length of the forward part 19 of the first described sleeve. This figure also illustrates a conventional soft jacket standard boat-tail bullet 14', familiar in the type of arm indicated. Its jacket 29 serves in place of the rotating band 15, and is engraved by the rifling of the barrel, with the same effect.

Although marked increase in gun life is obtained without shielding that section 26 of the bore surface beyond the protective sleeve 16', we prefer to face this section, including land and groove surfaces, with erosion resistant and corrosion resistant material such as chromium, or other material, as, molybdenum, tungsten or tantalum, in normal or hardened condition. The advanced facing thus constituted, preferably, and for best results, may be electro-deposited or otherwise formed to such thickness as will prevent the formation of heat-transformed layers in the underlying gun metal. By using the advanced facing, the length of sleeve on the case ammunition may be shortened as compared with the length desirable when the lining is omitted. It will be understood, however, that the shortening of the protective sleeve is not essential, and also that a shortened sleeve may be used without necessarily facing any parts of the gun bore with harder metal.

Illustrative of that embodiment of our invention which includes the advanced lining or facing, a gun barrel 30 rifled from adjacent the forcing cone 31 to the muzzle is shown in part in Fig. 6 of the drawing (the muzzle being omitted). It has a thin, adherent, electrolytrically deposited chromium plate or facing 32 on the bore surfaces, extending continuously from the shoulder 34 of the chamber and across the forcing cone 31 beneath and adjacent the part 19' of the protective sleeve 16' of the cartridge case 11, and covering the advanced bore surface 26' up the barrel for a substantial distance, or all the way to the muzzle (not shown). A thickness of chromium plate ranging from 0.003 inch to 0.006 inch or more preferably is used as the facing 32 to prevent heat transformation or other objectionable modification of the underlying steel at least in the barrel beyond the sleeve 16'; and in such thickness the chromium of the thickness named, in automatic arms of considerable range of caliber, and specifically the .50 caliber Browning machine gun is found to remain intact over an exceptionally long period of use.

In this figure (6) the short sleeve 16' is shown, as in Fig. 3. The chromium plate 32 in the advanced bore section, deposited over the rifled steel, provides the standard caliber finished rifled bore surface.

While the whole bore of the barrel 30 upon which the facing 32 is to be applied must be tooled to a larger than standard radius for a given caliber to an extent corresponding to the thickness of the facing to be deposited, and a corresponding allowance made in the width of the lands as tooled, the bore radius must also be further enlarged in the neck part 33 forcing cone 31 and relieved or enlarged part 35 of the bore for the sleeve part 19' by an amount equal at least to the thickness of the wall of the sleeve.

In addition to the allowance in the width of the lands for the thickness of the facing there must be also an allowance for the thickness of the sleeve in the width of the lands in the part 35. Thus, if the lands in the advanced bore 26' are to have a given width of finished land face 36, the lands 37 as tooled in that part should be approximately 0.006 inch narrower where the facing 32 is to be 0.003 inch thick. In the enlarged bore 35, however the tooled lands 38 should be approximately 0.026 inch narrower, where the rotating ring is to require no material further engraving after leaving the sleeve. If it is desired that there shall be some small degree of further engraving performed by the bands of the forward bore 26' the lands 38 may be reduced in height, that is, their radius increased somewhat further than the 0.013 allowance necessary for the sleeve and facing alone, and the reduction of width of the tooled lands 38 may be, say 0.027, instead of 0.026. The allowance of 0.026 inch would result in the interior surfaces of the sleeve part 19' being shaped by the band 15 to the same contour and measurements as the interior finished faces of the rifling of the advanced bore 26'. The greater allowance mentioned (0.027 inch) will insure that the material of the sleeve pressed into the rifling of the relieved part 35 will have an inner cross section surface form the same as that of the advanced bore, but differing sufficiently in dimension at the inner faces of the sleeve to require a slight additional engraving of the band 15 as the lands of the advanced part of the barrel are encountered. This construction, requiring relief of the neck for the facing 32 in addition to the allowance for the sleeve, results in shortening the shoulders 34 of the chamber as tooled but still affording an adequate stop for engaging the shoulder 12 of the cartridge. The step 39 between the enlarged bore 35 and the advanced bore 26' may be sloped as before at 25, in Fig. 4, or otherwise shaped as requirements dictate.

It is believed that the finished surfaces of the relieved part 35 may be such that a close alignment of all internal surfaces of the sleeve (as formed when pressed onto and into the rifling of the relieved part 35) with corresponding surfaces of the advanced bore 26' may be attained, so that less, or no further engraving of the band 15 will be required after it clears the sleeve.

In case the boat-tail bullet is used, the prior practice in raising the lands gradually from a cylindrical unrifled bore as at 41 of barrel 40 (Fig. 7) in advance of the neck of the chamber may be followed, as at 44 in Fig. 7. The relief 42 of the smooth bore for reception of our sleeve in such case would terminate short of the beginning of the lands 43, this beginning 44 of the lands being advanced forwardly in the bore if

necessary. In such case also, while the sleeve 16' is not shaped to rifle form on firing, as in the previously described gun, it will protect the bore from the severest erosion, corrosion, and plasticizing effects heretofore incident to rapid fire of the gun, so that the advanced bore lands 43 will be subject to less deterioration. And if the advanced bore 43 and relief 42 are faced as indicated at 45, its life is extended many times that of the conventional barrel in such guns.

Using the round of Fig. 6, the round is chambered in the barrel 20 so that the rotating band is directly behind the forcing cone 31, with the sleeve 16' tapering at 18' with the forcing cone, to the smaller diameter 19' over plated rifling of the relieved bore section 22'.

When a gun comprising barrel 30 of Fig. 6, with chambering case ammunition of the character there shown, is fired, the artillery type bullet 14 carries rotating band 15 past forcing cone 31, and engraving of the rotating band by the lands of section 22' acting through sleeve 16' ensues. The sleeve is also shaped to the plated rifling by pressure of the rotating band, at the same time that the latter is engraved. When the bullet reaches the end of the sleeve, additional engraving may take place directly on the plated rifling of the advanced bore section if there is lack of registry purposed or accidental of the shaped sleeve and advanced rifling. After firing, the case 11, with the sleeve positively attached by the keying means 20 as described is ejected from the gun, followed by loading, firing and ejection of similar sleeved rounds as described. The over-all effect is to relieve the gun barrel including forcing cone and rifled bore surface of exposure to the most severe conditions which normally contribute to erosion and plastic deformation, with the result that life of the gun is prolonged to a surprising extent. The chromium plating protects the advanced bore section from erosive effects and for itself is spared in large measure from mechanical effects set up by the bullet. Actually, as the invention has been heretofore practiced, the bullet is largely or wholly engraved before coming into direct contact with the plated bore surface.

The function as described is the same with either the long or short sleeve and artillery type bullet. The function with the conventional ball cartridge of Fig. 3 will be understood without detailing the sleeve simply protecting the smooth bore from erosion and deformation as will be understood, while the engraving of the bullet occurs conventionally on the faced lands 45.

The forcing cone and relieved surfaces for accommodating the forward reduced end of the sleeve are not regarded as part of the chamber of the gun, but the latter comprises only that enlarged part which accommodates the conventional cartridge case and extending from the breech face of the gun tube ordinarily, to the forward end of the neck portion 21. The chamber includes the shoulder 34 which receives thereagainst the shoulder 12 of the case 11. The surfaces forwardly of the forcing cone are regarded as parts of the bore technically so-called.

Results of numerous tests show that guns and ammunition provided and combined in accordance with our invention to a large extent reduce gun erosion and plastic deformation. The ammunition sleeves shield the breech bore surface from thermal, chemical and metallurgical, and mechanical effects combined, and in rifled guns make it possible when using raised rotating band ammunition to bring substantially pre-engraved

bullets to the rifling without any problem of orientation of the bullets in the barrel prior to firing. The erosion-resistant metal facing or lining on the advanced bore surface contributes much to the useful life of the guns, especially when provided in such thickness as to prevent heat alteration of the underlying steel and when afforded sleeve protection against initial stress and wear normally caused by engraving function and other forces.

In machine guns of the kind named herein there are recognized rates of fire (as, for instance, 800 shots per minute or more) which rapidly build up heat in the barrels, and it was a prior practice to limit the length of the "bursts," and require intervals between bursts sufficient to permit dissipation of the heat transferred to the barrel. In water cooled guns this tendency to heat is reduced but not entirely eliminated, and the interior faces will pass the critical temperature under sustained automatic fire. Air cooled guns will be more pronouncedly heated. In large caliber guns the frequency of fire may be of the order of thirty shots per minute, more or less, according to the caliber, but due to the larger charges of propellant used, the barrels still accumulate heat and the allotropic form of the barrel material changes, as earlier stated herein. With our changeable sleeve, using a new one on each shot, there may be approximated a balance (between transfer of heat to the barrel, and its diffusion in the barrel and dissipation by radiation, conduction and convection) in which a certain rate of fire may be sustained indefinitely, the sleeve shielding the barrel sufficiently, and its extraction removing heat before material transfer to the barrel, so that progressive dissipation of heat from the barrel may keep its mean temperature below a point of dangerous excess, especially adjacent the chamber in the part of the barrel ordinarily most subject to erosion. This will permit either continuous automatic fire as long as ammunition is available, or will permit much longer bursts at very high rates of machine gun fire; or more frequent firing of other types of guns.

Thus it will be seen that in the present invention guns and ammunition are provided and combined so as to prolong useful gun life, and that the objects hereinbefore noted together with many other thoroughly practical advantages are successfully achieved. The invention eliminates or minimizes many difficulties encountered in repair and replacement of eroded guns and the associated problems of production and transportation.

It will be understood that while the use of chromium facings such as coatings, claddings, sleeves or plates covering the bore surface from and in advance of the ammunition sleeve is preferred, the facings may be dispensed with entirely, or other erosion resistant metal, composite metal, or alloy metal facings employed where practical.

It will be understood that it is within the scope of our invention to modify conventional guns, as by machining or electropolishing the bore surface so as to make room for the ammunition sleeve with or without the advanced protective facing, or to provide guns initially which are suitable to receive the ammunition sleeve with or without the advanced lining or facing of the bore.

Since many possible embodiments of our invention may be made, and as many changes may be made in the embodiments hereinbefore set

forth, it will be understood that the matter described herein is to be interpreted as illustrative and not invariable.

We claim:

- 6 1. A round of ammunition comprising in combination a case body shaped to fit the chamber of a gun barrel, said case body shaped to hold a projectile, a projectile seated in said case body and projecting forwardly from the case body, said
- 10 projectile having an enlarged part deformable by a gun barrel when fired therethrough, conventional primer and propellant means in the case body, and a sleeve on the case body extending forwardly thereof around said projectile beyond
- 15 the enlarged deformable part, the sleeve shaped and proportioned to extend longitudinally within the bore of a gun barrel in which the round is loaded and in advance of said deformable part of the projectile so as to lie over the bore area
- 20 of principal erosive and corrosive tendency and means on said sleeve for positively retaining same on said case after the round is fired.
- 25 2. A round of ammunition comprising a case for conventional chambering in gun barrels, said case having an open forward end, a projectile seated in the forward end of said case and projecting therefrom, a thin sleeve in contact with said case and extending therefrom over at least a part of said projectile, and means for retaining
- 30 said sleeve attached to said case after the round is fired, said case being provided with a forwardly opening neck portion of reduced diameter and said projectile being of the banded artillery type and is seated partly within said neck portion and
- 35 partly protruding therefrom, said projectile having a rotating band of diameter greater than the neck of the case, and said thin sleeve being of erosion resisting material and extending from said neck snugly over said band and around the largest diameter of said projectile.
- 40 3. In combination a round of ammunition and a gun barrel, said round comprising a case, a projectile seated in the forward end thereof, and a thin ductile, erosion resistant sleeve attached
- 45 to and extending forwardly from said case over at least part of said projectile, said gun barrel comprising a rifled bore and a chamber for receiving said round, said chamber comprising a rifled section corresponding to the sleeve portion
- 50 of said round forwardly of said case, whereby said sleeve will be shaped by said rifling when the round is fired.
- 55 4. The invention as recited in claim 3 wherein the rifled section of said chamber is enlarged to an extent equal to the thickness of said sleeve, the rifling of said enlarged bore being aligned with the rifling of the advanced bore, the width of the lands of said rifling of the enlarged bore being reduced correspondingly, wherein the rotating band of a projectile fired therein will be engraved on the inserted sleeve to match the rifling of said advanced bore section.
- 60 5. A combined ammunition round and gun bore protecting device comprising a conventional ammunition round proportioned to fit a gun barrel having a conventional forcing cone, including a projectile and a sleeve of erosion resistant material fixed as a part of the round unit, said sleeve having a reduced forward part extending forward around the projectile beyond the normal line of securement of the projectile in the round and reduced so as to extend forwardly of the forcing cone of a barrel in which the round is inserted and to lie upon the bore surface of such barrel a substantial distance beyond the forcing

cone, and means on said sleeve for positively retaining same in a gun barrel after the round is fired, the projectile having a part of a diameter and material such as to be engravable by rifling of a rifled bore barrel in which the round is fired, and said sleeve being ductile and capable of shaping to underlying rifling in such bore by pressure and conformation of the engravable part of the projectile to the so-shaped sleeve while supported by such underlying rifling.

6. A combined ammunition round and gun bore protecting device comprising a conventional propellant charge, primer and container, a projectile extended forwardly therefrom and having an exposed part engravable by bore rifling, and a sleeve of erosion resistant material fixed as part of the round unit and having a part extended forwardly around the projectile beyond said engravable part so as to extend into the bore of a barrel in which the round is inserted and to lie upon the bore surface of such barrel over a substantial distance beyond the chamber of such barrel and cooperating locking means on said sleeve and retainer for retaining said sleeve locked to said container

after the round is fired, said means being operable by gas pressure due to firing.
